UNITED STATES PATENT OFFICE.

JOHN D. CROSS, OF ALHAMBRA, CALIFORNIA.

CEMENT-BLOCK MACHINE.

Application filed May 12, 1922. Serial No. 560,311.

To all whom it may concern:

Be it known that I, JOHN D. CROSS, a citizen of the United States, residing at Alhambra, in the county of Los Angeles and State of California, have invented certain new and useful Improvements in a Cement-Block Machine; and I do hereby declare the following to be a full, clear, and exact description of the invention, such as will enable others skilled in the art to which it appertains to make and use the same.

The object of the invention is to provide a cement block forming or molding machine of efficient and improved construction capable of accurate and comparatively rapid operation in the molding of blocks of variable sizes and types designed for building purposes and suitable for actuation either by power or manually at the option of the operator or according to whether or not power is available; and with these general objects in view the invention consists in a construction, combination and relation of parts of which a preferred embodiment is illustrated in the accompanying drawings, wherein:

Figure 1 is a side view of the machine showing the mold box in its lowered and the tamper in its elevated position.

Figure 2 is a similar view partly in longitudinal section showing the mold box in its elevated and the tamper in its depressed or tamping position.

Figure 3 is an end view with the parts in the position indicated in Figure 2.

Figure 4 is a vertical sectional view on the plane indicated by the line 4—4 of Figure 1.

Figure 5 is a plan view.

Figures 6 and 7 are transverse horizontal sections on the planes indicated respectively by the lines 6—6 and 7—7 of Figure 2.

Figure 8 is a detail view in perspective of the mold box, partly broken away to show the construction and means of mounting the cores therein.

Figure 9 is a similar view of the operating lever mechanism.

Figure 10 is a similar view of the mold box guide and palate support and the means whereby the same is sustained in position for adjustment to produce blocks of different dimensions.

Figure 11 is a vertical sectional view of the lower portion of the machine with the cores in the mold box.

Figure 12 is detail bottom plan view of the mold box and cores.

The apparatus embodies a frame work having uprights 20 connected longitudinally by the side beams 21 and transversely by the end bars 22 and at their upper ends by suitable bracing elements 23, and beams 21 which are preferably of the cross sectionally angular form serving to sustain racks 24 which constitute a support for a pallet 25, separable from the mechanism as a means of removing the completed cement blocks from the machine. These racks consist of frames disposed in parallel relation with flanges 26 at their lower edges for attachment by bolts 27 to the beams 21, the horizontal elements of said beams being transversely slotted as indicated at 28 to permit of transverse adjustment of the racks to suit pallets of different dimensions designed to support blocks of different sizes determinable by the dimensions of the mold box 29 which is mounted for vertical movement with relation to and about the racks 24 and is provided with terminal brackets 30 which are slidably mounted upon guide rods 31 supported by the main frame, sleeves 32 at the ends of said arms being fitted with bushings 33 to slide on the rods which at their upper ends are secured to the transverse bars 22 and at their lower ends are stepped in the base bars 34.

The mold box is of dimensions to receive the pallet 25 and carries cores 35 which may be varied as desired in size and arrangement, the pallet having openings 36 through which the cores extend when the mold box is in the elevated or molding position indicated in Figures 2 and 3, and suspended above the mold box in position to be dropped into contact with the contents of the same for consolidating the cement is a tamper 37 consisting for example, as indicated, of a weighted box carried by a cross head 38 of which the extremities are attached to guide bars 39 operating in guide openings 40 in the upper braces 23 of the frame and similar guide openings in the cross bars 22. The tamper is held in its elevated position by a latch 40 pivoted as at 41 to the frame work and adapted to engage a loop or catch 42, said latch being held in engaging relation with the catch by a suitable spring 43 and being movable to release the tamper by means of a trip lever 44. The guide bars 39 also carry rack teeth 45 for engagement by pinions 46

on the operating shaft 47 which may be either power driven by a pulley 48 or manually driven by a crank 49, a clutch 50 being provided for coupling the pulley to the shaft 5 when the tamper is to be raised by power. The clutch shifting lever 51 is arranged in the path of a trip cam 52 on the end of the cross head 38, so that after the tamper has been dropped to compress the charge in the 10 mold box and the clutch has been adjusted to connect the pulley with the drive shaft to raise the tamper, the cam 52 will disengage the clutch as the tamper reaches the limit of its upward movement where it is engaged 15 and held by the latch 40. Obviously the disengagement of the latch by the operation of the trip lever 44 will permit the tamper to drop with force depending of course upon its weight sufficient to efficiently compress 20 or consolidate the contents of the mold box, and when the tamper has been elevated and the box depressed to expose the molded block, the latter may be removed with the pallet to permit of drying and hardening. 25 The means for elevating and depressing the mold box, consists of a rock shaft 53 mounted in suitable bearings 54 on the supporting frame and having crank arms 55 connected by links 56 with the mold box. 30 The ends of the shaft are squared or similarly shaped to form wrench seats 57 to receive an operating lever 58, which thus may be used at either side of the machine (or at both) to suit the convenience of the operators. 35

The core blocks in the mold box are supported by parallel longitudinal bars 63 arranged in the box and longitudinally extending bolts 64 passing through the cores are 40 engaged with washer plates 65 spanning said bars to clamp the cores in place at the desired intervals or spacement to suit the character of the blocks to be molded.

From the foregoing description it will be 45 obvious that the mold box is arranged in telescoping relation with the means, consisting in the construction illustrated of the racks 24, by which the pallet is supported, so that while the mold box with its contained 50 cores is in proper relation with the pallet to adapt the latter to perform the function of the bottom of the mold box when the latter is elevated to receive the cement and the impact of the tamper, the mold box is 55 adapted to be withdrawn downwardly from the block thus molded and into housing relation with the racks 24 to entirely release the molded block for removal from the machine without the risk of distorting or disturbing 60 the parts thereof; and owing to this relative arrangement and operation of the parts in connection with the elements employed for effecting such operation, a relatively rapid and accurate molding of blocks of the desired dimensions may be accomplished with- 65

out necessitating the employment of skilled operators and hence with a desirable economy in the cost of manufacture.

Having thus described the invention, what I claim is:

1. A cement block molding machine having a vertically movable mold box, means in telescoping relation with the box for supporting a removable pallet, and means for raising and lowering the box, the means for 75 supporting the pallet consisting of parallel beams arranged beyond the path of movement of the box and racks arranged within the area of the box and supported by said beams.

2. A cement block molding machine having a vertically movable mold box, means in telescoping relation with the box for supporting a removable pallet, and means for raising and lowering the box, the means for supporting the pallet consisting of parallel beams arranged beyond the path of movement of the box and racks arranged within the area of the box and supported by said beams, the racks being adjustable relative to the beams to accommodate different dimensions of the box. 85

3. A cement block molding machine having a vertically movable mold box, means in telescoping relation with the box for supporting a removable pallet, and means for raising and lowering the box, the mold box having longitudinal parallel bars at its bottom and cores detachably and adjustably secured to and supported by said bars. 95

4. A cement block molding machine having a vertically movable mold box, means in telescoping relation with the box for supporting a removable pallet, and means for raising and lowering the box, the mold box having longitudinal parallel bars, cores seated upon said bars, bolts extending longitudinally through the cores, and washer plates spanning the bars and engaged by said bolts for adjustably securing the cores to the bars. 105

5. A cement block molding machine having a vertically movable mold box, means in telescoping relation with the box for supporting a removable pallet, means for raising and lowering the box, and a tamper normally suspended above the box for gravitational movement into consolidating relation with the contents thereof, and having elevating means consisting of guide bars provided with racks, a drive shaft having pinions in engagement with said racks, and means for actuating the drive shaft. 115

6. A cement block molding machine having a vertically movable mold box, means in telescoping relation with the box for supporting a removable pallet, means for raising and lowering the box, said pallet being surrounded by and forming the bottom of the box when the latter is elevated, a tamper 125

- normally suspended above the box for gravitational movement into consolidating relation with the contents thereof, a latch for engaging and supporting the tamper in its elevated position, means for elevating the tamper into engaging relation with said latch, and means for disengaging the tamper from the elevating mechanism when it reaches the limit of its upward movement.
- 10 7. A cement block molding machine having a vertically movable mold box, means in telescoping relation with the box for supporting a removable pallet, means for raising and lowering the box, a tamper normally suspended above the box for gravitational movement into consolidating relation with the contents thereof, a latch for engaging and supporting the tamper in its elevated position, means for elevating the tamper into engaging relation with said latch, and means for disengaging the tamper from the elevating mechanism when it reaches the limit of its upward movement, the means for elevating said tamper consisting of a drive shaft having pinions in engagement with racks on said tamper, and a clutch for coupling the shaft to a power driven pulley, and means for releasing the tamper consisting of a trip carried thereby for disengaging said clutch.
- 15 8. A cement block molding machine having a vertically movable mold box, means in telescoping relation with the box for supporting a removable pallet, means for raising and lowering the box, a tamper normally suspended above the box for gravitational movement into consolidating relation with the contents thereof, a latch for engaging and supporting the tamper in its elevated position, means for elevating the tamper into engaging relation with said latch, and means for disengaging the tamper from the elevating mechanism when it reaches the limit of its upward movement, the means for elevating said tamper consisting of a drive shaft having pinions in engagement with racks on said tamper, and a clutch for coupling the shaft to a power driven pulley, and means for releasing the tamper consisting of a trip carried thereby for disengaging said clutch.
- 20 9. A cement block molding machine having a vertically movable mold box, means in telescoping relation with the box for supporting a removable pallet, means for raising and lowering the box, a tamper normally suspended above the box for gravitational movement into consolidating relation with the contents thereof, a latch for engaging and supporting the tamper in its elevated position, means for elevating the tamper into engaging relation with said latch, and means for disengaging the tamper from the elevating mechanism when it reaches the limit of its upward movement, the means for elevating said tamper consisting of a drive shaft having pinions in engagement with racks on said tamper, and a clutch for coupling the shaft to a power driven pulley, and means for releasing the tamper consisting of a trip carried thereby for disengaging said clutch.
- 25 10. A cement block molding machine having a vertically movable mold box, means in telescoping relation with the box for supporting a removable pallet, means for raising and lowering the box, a tamper normally suspended above the box for gravitational movement into consolidating relation with the contents thereof, a latch for engaging and supporting the tamper in its elevated position, means for elevating the tamper into engaging relation with said latch, and means for disengaging the tamper from the elevating mechanism when it reaches the limit of its upward movement, the means for elevating said tamper consisting of a drive shaft having pinions in engagement with racks on said tamper, and a clutch for coupling the shaft to a power driven pulley, and means for releasing the tamper consisting of a trip carried thereby for disengaging said clutch.

In testimony whereof I affix my signature in presence of a witness.

JOHN D. CROSS.
